INVENTOR.

Thomas R. O'Malley

UNITED STATES PATENT OFFICE

2,279,718

STAPLE FIBER CUTTER

Thomas R. O'Malley, Wilmington, Del., assignor
to American Viscose Corporation, Wilmington,
Del., a corporation of Delaware

Application September 24, 1941, Serial No. 412,127

5 Claims. (Cl. 164—61)

This invention relates to the cutting of staple fibers from bundles of continuous filaments and more particularly to improvements in that type of apparatus which involves the use of centrifugal force in drawing the bundle of filaments to be cut into the path of a knife, such as is described in the Beria Patent 1,723,998.

It is an object of the invention to replace the stationary cutting knife of the patent with a rapidly moving knife which swipes across the filament bundle at a high rate of speed compared to the velocity of motion of the filament in the other direction.

It is a further object of the invention to provide a simple and effective arrangement of apparatus for adapting staple fiber cutters of this type to the operation of such a moving knife.

Further objects of the invention will be apparent from the drawing and description thereof that follows hereinafter.

In the drawing, illustrative of the invention, Figure 1 is a plan view of the apparatus, and Figure 2 is an elevational view partially in cross-section.

As shown in the drawing, the apparatus comprises a centrifugal disk 2 having the axial entrance channel 3 connected with the radial channel 4. The disk is mounted for rotation with the shaft 5 within the bearings 6 and 7 on a suitable support 9. Motive power is supplied to the pulley 10 on the shaft by means of a motor and belt not shown. A stationary gear 11 is suitably fastened to the bearing support, such as by means of the hub 12 extending annularly therearound.

The disk itself is formed with the radially outwardly extending flange 13 in which, adjacent the opening 14 of the radial channel within the disk 2, a shaft 15 is mounted for rotation. A suitable bushing 16 of bearing metal may be inserted between the shaft 15 and the flange opening 17. The shaft has a disk 18 fastened to one end thereof and a gear 19 on the other end in mesh with the gear 11 so that as the centrifugal disk 2 rotates, the small disk 18 rotates with the shaft 15 as the gear 19 walks about the stationary gear 11. The small disk 18 carries a knife 20 or other cutting means so arranged as to be brought in close proximity or substantial contact with the centrifugal disk adjacent the opening 14 of the radial channel so that each rotation of the knife through this position results in cutting of the staple fibers. The disk 18 may be balanced by any suitable counterweight 21.

While a preferred embodiment of the invention

has been disclosed, the description is intended to be illustrative only, and it is to be understood that changes and variations may be made without departing from the spirit or scope of the invention as defined by the appended claims.

What I claim is:

1. In apparatus of the class described, centrifugal means for continuously feeding a filamentary bundle outwardly therefrom and means for swinging a cutting blade at intervals transversely of said bundle in a direction opposite to the direction of rotation of the filamentary bundle as it is fed by said centrifugal means.
2. In apparatus of the class described, centrifugal means for continuously feeding a filamentary bundle outwardly therefrom and means for rotating a cutting blade in a path substantially coplanar with and substantially tangent to said centrifugal means adjacent the point of emergence of the filamentary bundle therefrom.
3. In apparatus of the class described, centrifugal means for continuously feeding a filamentary bundle outwardly therefrom, rotatable cutting means for cutting said filamentary bundle at intervals as it is fed outwardly, means for rotating said cutting means about its axis and simultaneously moving said axis in a circular path concentric with the centrifugal feeding means.
4. In apparatus of the class described, a rotatable disk having an axial channel for entrance of a filamentary bundle and a radial channel connected thereto for discharge of the bundle therefrom, a member extending radially outwardly from said disk, cutting means journaled in said member in substantial alignment with said radial channel for rotation substantially tangentially of said disk, and means for rotating said cutting means about its axis in a direction opposite to the direction of rotation of said disk.
5. In apparatus of the class described, a rotatable disk having an axial channel for entrance of a filamentary bundle and a radial channel connected thereto for discharge of the bundle therefrom, a member extending radially outwardly from said disk, cutting means journaled in said member in substantial alignment with said radial channel for rotation substantially tangentially of said disk, a stationary gear arranged concentrically with respect to said cutting disk and a second gear secured to the journal of said cutting means and in mesh with said stationary gear.

THOMAS R. O'MALLEY.
